UNITED STATES PATENT OFFICE.

NATHAN DAVIS, OF AUGUSTA, GEORGIA.

MANACLE.

SPECIFICATION forming part of Letters Patent No. 349,696, dated September 28, 1886.

Application filed August 17, 1886. Serial No. 211,154. (No model.)

To all whom it may concern:

Be it known that I, NATHAN DAVIS, a citizen of the United States, residing at Augusta, in the county of Richmond and State of Georgia, 5 have invented a new and useful Improvement in Manacles, of which the following is a specification.

My invention is an improved manacle, of the peculiar and novel construction hereinafter described, and particularly noted in the claims.

The object of my invention is to provide a manacle to be used as a substitute for straight-jackets and handcuffs, for securing the hands of lunatics and other prisoners, to prevent them 15 from injuring their person or doing damage to others.

In the accompanying drawings, Figure 1 is a view showing my manacle secured in position upon the body of a person; and Fig. 2 is 20 a view of the manacle detached, or when not in use. Fig. 3 is a longitudinal section thereof.

Referring by letter to the drawings, my improved manacle consists of a belt, A, constructed of stout and pliable leather or heavy 25 flexible rubber. One end, B, of this belt is cut narrow or reduced in size, and is provided with openings b, for a purpose to be explained. Attached to the opposing end of the belt A is a buckle, C, which receives the reduced end B of the belt, and by reason of the openings b the belt is secured or fastened around the waist of a person.

It will be observed that I provide a number 35 of openings, b, so that the manacle is capable of accommodating itself to waists of different sizes, as may be found necessary.

To the front portion of the belt A, but at a distance apart, are secured loops or bands, 40 which form cuffs D and D', that are adapted to receive the hands. These cuffs are of a conical shape, their inner ends being smaller than their outer ends, for a purpose presently to be explained.

To the inner side of the belt, and to one side 45 of the large ends of the conical cuffs D and D', are secured retaining-strips E and E', provided with buckles e and e', for fastening the wrists in position.

From the foregoing description, taken in 50 connection with the drawings, the manner of using my manacle will be readily understood.

The belt is passed around the waist of a per-

son and secured in place by the strap B and buckle C, as described, the conical cuffs or loops being in front of the person. The hands are then inserted through the large ends of the said conical loops or cuffs D and D' and pushed as far in the cuffs as necessary. The securing or retaining straps E and E' are then passed 60 around the wrists of the person, confining the hands firmly in the loops or cuffs, and all efforts on the part of the person to free himself will be resisted.

It will be observed that, by the conical shape 65 of the loops or cuffs, when the hand is pushed down to a certain place it can go no farther, as the other end is so small as to entirely prevent the use of the fingers, and when fastened or retained in this position the hands cannot 70 be used. It will also be noticed that my manacle is especially useful in surgical operations when it is necessary that the hand be confined and use of the fingers prevented. It will further be seen that my improved manacle is not 75 uncomfortable to the person, as it does not hurt the wrist or hand, being made of soft pliable material. If desired, the conical retaining loops or cuffs may be lined with cloth or other soft material.

My device combines extreme simplicity in 8c construction with general efficiency, and being very inexpensive will prove to be a very useful article in asylums, for surgeons, and in confining all persons of a dangerous character. 85

I claim—

1. The herein-described manacle, comprising belt A, having conical loops or cuffs D and D', secured to the belt and receiving the hands, and means for retaining the hands in the loops 90 or cuffs, as set forth.

2. The herein-described manacle, comprising belt A, having loops or cuffs D and D', conical in shape, secured thereto, and adapted to receive the hands, and the retaining or securing straps E and E', adapted to pass around 95 the wrists to secure the hands in the loops or cuffs, as set forth.

In testimony that I claim the foregoing as my own I have hereto affixed my signature in 100 presence of two witnesses.

NATHAN DAVIS.
